UNITED STATES PATENT OFFICE.

HENRY J. SCHAEFER, OF ASHTABULA, OHIO.

PRESSURE DRAFT GEAR.

Application filed December 1, 1920. Serial No. 427,529.

To all whom it may concern:

Be it known that I, HENRY J. SCHAEFER, a citizen of the United States, residing at Ashtabula, in the county of Ashtabula and State of Ohio, have invented certain new and useful Improvements in a Pressure Draft Gear, of which the following is a specification.

This invention relates to compression draft gear for railroad cars.

The object of the invention is to provide a mechanism whereby the pull of a railroad car is proportionately distributed throughout the car and the entire pull being borne by the draw bar prevented.

Another object is to provide a simply constructed and efficient mechanism of this character which may be made to fit any sized car.

With these and other objects in view, the invention consists in certain novel features of construction as hereinafter shown and described, and specifically pointed out in the claims.

In the accompanying drawings:

Figure 1 represents a top plan view partly in section of the apparatus shown applied;

Fig. 2 is an enlarged transverse section taken on the line 2—2 of Fig. 1;

Fig. 3 is an enlarged detail side elevation of one of the friction plates employed in the apparatus;

Fig. 4 is a detail sectional view, showing the connection of draft bar with the gear;

Fig. 5 is a side elevation of one of the compression plates taken from the outside;

Fig. 6 is a side elevation of one of draft keys;

Fig. 7 is a similar view of one of the spacers;

Fig. 8 is a detail end elevation showing the draft bar supporting hanger;

Fig. 9 is a detail sectional view taken on line 9—9 of Fig. 8.

Fig. 10 is a horizontal section of the center block, taken on the line 10—10 of Fig. 11; and

Fig. 11 is a side elevation of said block.

The gear constituting this invention comprises a center block 1 constructed of malleable steel and provided at its opposite ends with coupler butt shanks 2 for connection with draw bars D. This block 1 has a centrally disposed oblong aperture 4 extending therethrough the end walls of which

converge toward the middle of the block meeting at a point about midway the thickness thereof (see Fig. 10). This block 1 also is provided with a plurality of apertures 3 one arranged at each corner thereof and adapted to receive draw pins 19 which are preferably constructed of forged steel. The oblong opening 4 in the block 1 has the ends 6 thereof rounded (see Fig. 11) to prevent shearing of the draft compression rods 20 which are designed to be mounted therein and which will be hereinafter more fully described.

Two forged steel draft plates 7 are designed to fit between the center block 1 and the steel underframe F of the car. These plates are each provided with four draw pin apertures 8 and with a centrally disposed oblong opening 9 which is beveled at each end and at each side to prevent shearing of the compression rods 20 since these plates are designed to be reversible. A draft key opening 10 is located at each end of the plate 7 in which openings draft keys 26 are designed to be mounted. These keys 26 are preferably constructed of forged steel plates and are designed to pass through compression plates 11 one arranged outside each of the frame members F and riveted thereto, and through the car underframe F, the draft plates 7 and through the draw bars D. One end of each of these keys 26 is bent over or flanged as shown at 27 to prevent the key from pulling through the plate while the other end thereof is notched as shown at 28 and also provided with an aperture 29. Two malleable iron spacing plates as 30 fit on the notched ends of the draft keys 26 and each is provided with a projection 32 to fit in the notch 28 of its respective draft key 26, cotter pins being preferably passed through the draft key opening 29 to hold the parts assembled.

The two malleable steel compression plates 11 which are mounted outside the angle iron frame members F on the compression rods 20 are provided each with two spring seats 12 which are inclined in opposite directions preferably at a pitch of about 80 degrees and each has a flange 13 arranged thereon to prevent the spring seated thereon from slipping laterally. These seats 12 each has an obliquely disposed aperture 14 extending therethrough through which the rods 20 are designed to pass, said rods extending at op-

posite ends beyond the seats and having mounted thereon coiled compression spring 24 held in position by nuts 22 provided at their inner ends with integral washers 22^a, 5 said nuts being screwed on the outer ends of the rods 20 which are threaded for this purpose, the nuts having cotter pin apertures 23 therein for locking them to the rods.

The plates 11 are each provided at opposite ends with longitudinally extending elongated openings 15 through which the draft keys 26 pass which openings are surrounded on the outer faces of the plates by flanges 15^a. These plates 11 are secured to 10 the car underframe F by a plurality of rivets and bolts, the heads of the rivets and bolts being flush with the inner faces of the members F to provide for clearance of the friction plates 7.

20 Two of the draft compression rods 20 are employed being preferably constructed of wrought iron and bent midway their ends at an angle of about 160°. These rods pass through the oblong opening 4 in the center block 1 through the oblong openings 9 in the draft plates 7, openings in the frame members F, and the openings 14 in the compression plates 11 as hereinbefore described. As above stated these rods 20 are provided 25 at their opposite ends with the draft springs 24 which are employed for compressing and absorbing shocks and distributing the pull.

From the above description it will be obvious that in the mechanism herein shown 30 and described and which is mounted beneath the car adjacent and between the inner ends of the draw bars, so that on a pull the draft plate 7 will compress the springs 24. The compression of the springs 24 is controlled 35 by the length of the slots or openings 15 in the plates 11.

The draw bars D have their coupler head carrying ends supported in hangers 40 depending from the end members of the car frame, while their inner ends have transverse apertures for passage of the draft keys 26 and are socketed to receive the coupler butt studs 2 on center block 1 being connected thereto by pins 35. As shown these 40 hangers 40 are U-shaped and the legs 41 thereof are mounted in a head block 42 being secured thereto by a pin 43. The blocks 42 each has apertured lugs 44 extending rearwardly therefrom and passing through 45 the car frame end members and secured by headed pins 45.

The assembling of the apparatus on the underframing F of the car is obvious from an inspection of Figs. 1 and 2, and it is 50 described as follows:

The plates 11 are first bolted or riveted to the outer faces of the two members F with the openings 14 and 15 in said plates registering with corresponding openings 60 (see Fig. 1) in said members F. The block

1, and plates 7 are then connected by the pins 19 and are slipped into position between the members F as shown in Figs. 1 and 2. The studs 2 of block 1 are then entered in the socketed inner ends of the draw bars D and secured by the pins 35. The notched ends of the keys 26 are then passed through the openings 15 in one plate 11, through the adjacent members F through 70 openings 10 in plates 7, through the inner 75 ends of the draw bars, then through the openings 10 in the other plate 7, through the other member F, openings 15 in the other plate 11 and has mounted on said projecting ends the spacing plates 30 and are 80 secured by cotter pins passed through the openings 32^a in plates 30 and those 29 in the keys.

One of the rods 20 with one spring 24 thereon is then passed through one of the 85 apertures 14 in one of the outer fixed plates 11 through the corresponding opening in the adjacent frame member F, then through the opening 9 in the adjacent inner sliding plate 7, through the opening 4 in block 1, then through the opening 9 in the other sliding plate 7, through frame F, through one of the openings 14 in the other outer fixed plate 11. The other spring 24 is then placed on 90 said rod 20 and the nut 22 applied, it being of course understood that the inner ends of the springs 24 are positioned in the seats 12. The other rod 20 is similarly applied, 95 it of course being obvious that one rod 20 is arranged at one end of the opening 4 of the block 1 and the other rod at the other end with their bent central portions conforming in shape to and engaging the end walls of said opening 4 so that the spring 100 carrying ends of one rod will be inclined 105 forward and those of the other rod rearward.

To assemble the device there is provided a center block 1 with one coupler butt shank 2 on each end of the block and there are 110 four two-inch holes for draw pins 3 located at each corner of the block. The block has an oblong hole 4 which may be three by eleven inches reduced at the middle to three by nine inches.

The corners of the oblong hole are made 115 round to prevent shearing of the draft compression rods 20 at the bend where they pass through the center of the block, as shown at 6, Figs. 10 and 11.

As shown in Fig. 3, there are two forged 120 steel draft plates to fit between the center block and steel under frame of the car. Four draw-pin holes 8 are located two inches from the top and bottom of each plate and 125 thirteen and three-fourths inches apart. These plates, shown in Fig. 3, are lifted up until the holes 8 match the holes in the draw sills and until the slots 10 in the showing 130 of Fig. 3 match the hole 15 in Fig. 5. Also

the holes 14 in Fig. 5 should match the center block hole in the draft plate 7 of Fig. 3 and the center block hole 4 in Fig. 11.

The rods 20 are threaded four or five inches from the ends and each there has a slotted key way 23, as before described, to receive a cotter pin to prevent the nuts from backing off. After one rod 20 is applied then the other rod 20 is applied in the same manner, sufficient clearance being provided for the purpose, see Fig. 1.

After the rods 20 are applied the springs 24, washers 22^a and nuts 22 are applied to all four ends of the rods 20 and partially drawn up, to be subsequently drawn up to a greater extent.

In practice the draft gear has a little more than three and seven eighths inches of spring motion (one and seven eighths inches each way).

To disassemble the device, the operation described is reversed, a lifting jack being used to relieve the weight until the rods 20 are released.

25 What is claimed is:

1. In an apparatus of the class described, the combination with a draw bar; of pull distributing means, and a connection between said means and bar whereby a pull 30 on the bar will be distributed throughout the car.

2. In an apparatus of the class described, the combination with a draw bar; of pull distributing means connected therewith and comprising a longitudinally movable member, a connection between said member and bar, means compressible in a plane at right-angles to the movement of said bar and operable through said member by a pull on 40 said bar.

3. In an apparatus of the class described, the combination with a draw bar; of pull distributing means connected therewith and comprising a longitudinally movable member, a connection between said member and bar, compression springs arranged on opposite sides of said member and compressible in a plane at right angles to the movement of said bar and operable through said member by a pull on said bar, and means carried by said member and connected to actuate said springs on the exertion of a pull on said bar.

4. In an apparatus of the class described, 55 the combination with laterally spaced frame members, and a draw bar mounted to move between them; of a block mounted to move between said frame members, a connection between said block and bar, said block having an elongated aperture extending transversely therethrough, compression plates located outside and fixed to said frame members and each having an aperture registering with the aperture in said block and an inclined spring seat on the outer face of each,

draft plates carried by said block between it and said frame members and movable therewith and each having an aperture to register with those in the block and compression plates, an acute angled rod extended 70 through the registering apertures in said plates and block and projecting at opposite ends beyond said compression plates, and coiled springs mounted on said projecting rod ends in the seats of the compression 75 plates whereby a pull on said draw bar will operate to compress said springs and distribute the pull.

5. In an apparatus of the class described, the combination with laterally spaced frame 80 members and a draw bar mounted to move between them; of a block mounted to move between said frame members, said block having an elongated aperture extending transversely therethrough, compression plates located outside and fixed to said frame members and each having an aperture registering with the aperture in said block and an inclined spring seat on the outer face of each, draft plates carried by said block between 90 it and said frame members and movable therewith and having an aperture to register with those in the block and compression plates, draft keys extending through said plates and draw bar, being movable in said 95 compression plates and with said draft plates, an acute angled rod extended through the registering apertures in said plates and block and projecting at opposite ends beyond said compression plates, and coiled springs 100 mounted on said projecting rod ends in the seats of the compression plates whereby a pull on said draw bar will operate to compress said springs and distribute the pull.

6. In an apparatus of the class described, the combination with laterally spaced frame members, and a draw bar mounted to move between them; of a block mounted to move between said frame members, a connection between said block and bar, said block having an elongated aperture extending transversely therethrough, the end walls of which converge toward the center of the block and rounded, compression and draft plates carried by said frame members, the former 110 being fixed and the latter movable relatively thereto, said plates having apertures registering with each other and with that in the block, a rod extending through said registering apertures, coiled springs on said rod 115 ends, and abutments on said ends between which and said compression plates the coiled springs are located.

7. In an apparatus of the class described, the combination with laterally spaced frame 125 members, and draw bars mounted to move between them; of a block mounted to move between said frame members, a connection between said block and bars, said block having an elongated aperture extending trans-

versely therethrough, the end walls of which converge toward the center of the block and rounded, compression and draft plates carried by said frame members, the former being fixed and the latter movable relatively thereto, said plates having apertures registering with each other and with that in the block, acute angled rods extending through the registering apertures in said plates and

blocks, and projecting at opposite ends beyond the compression plates with nuts on the terminals thereof, and coiled springs on said rod ends between said nuts and compression plates.

In testimony whereof, I affix my signature hereto.

HENRY J. SCHAEFER.
